N. L. MOORE.

Crimping Leather.

Patented Feb. 4, 1812.

1658X
Nathaniel S. Moore
Sellers Patent

The individual referred to in this Sellers Patent and marking, first of the same
containing a description in the words of the said Nathaniel S. Moore him-
self of his machine for cramping Boot Legs.

This machine consists of the bench, upright binders, side boards, and boot
legs. The Bench is a horizontal block or board of iron dimensions so as
convenient. It rests on four feet, whose size & arrangement height from
the floor, and it supports the other machinery. The upright binders are
two vertical posts, which rise from the Bench, having their lower extrem-
ities fixed into it by tenons, or the tenons may go through the bench
and be secured underneath by pins or wedges. They stand so far apart
as to allow the side boards and rubbers, & also the boot legs to
stand between them. The number of these binders to be increased if more
rubbers and boot legs than one set are on the same bench; so that one
set of boot legs, rubbers and side boards may be between two upright
binders. These upright binders are kept in their proper position by ^{horizontal} bars
which connect the upper ends, and which regulate their distance according
to the thickness of the leather in the legs. Between these binders and
attached thereto are two side pieces, & far apart as to take the boot legs
leather when cramped between them. They rest on the bench having
their further ends reaching to the back edge of the upright binders.
The upper edge of the further end is formed into the arc of a circle the
thickness of the board being there so reduced as to admit one of the rubbers
between it and the upright binder on each side; the inner edge of the rubber
passing along this circular part of the side board, and past the boot leg.

The rubber is composed of two parallel arms or tynes connected at their
extremity so as to work together and form the handle by which it is moved;
it turns between the side boards and binders on pivots, which expand into
them. At the end of the arms, where these pivots are, is placed the rubber
which rises from them, and reaches above the circular part of the side boards
there standing inwards to the inner edge of the side boards. The upper ends

of these will be conformed to a semicircle, and they press up the leather
on each side of the Boot tree, gathering so as to form or draw the leather
into the proper shape for Boot-making. The Boot tree is composed of
three parts. The Boot tree proper. The first binder, which has the same
curve as the tree and has a groove along it which receives the edge of the
tree and the second binder, that forms the back of the Boot leg upon
the first binder, in the same manner that the first binder receives
the front of the Boot leg to the tree. At the lower extremity of
the tree is a projecting hook which is fixed into a staple on the head
of the post rising from the bench behind the upright binders, and
which staple serves as a fulcrum when the tree is forced down be-
tween the side boards, and the operation of rubbing is performed.

A plate of metal and some slender frames from the end of the
tree the hook above mentioned is fixed upright, the end of the first binder
to of the tree while the other end of the tree is held up to the tree, the un-
der or second binder has one end that goes into the notch in the first
binder, and is held to it at the other end by a spring catch secured
or iron. to these binders and the tree may be fastened to each other
near the farther end, in any other manner, as by bolts,
pins, staples &c. In using this machine the leather which
forms the front of the boot, is placed between the Boot ^{tree} and first
binder, the instep being between the tree turning downward, and that
part of the leather which forms the back of the boot, between the first
and second binder, above described the leather may be single or double
at the pleasure of the person using the machine. The horse at
the sides and of the tree, is then introduced into the staple on the post
and round the opposite end of the tree drawn downwards by a strap
with the feet or in any other manner, and as this downward pressure
is given the handle of the rubber is raised and lowered so that the motion
of the rubber in the arc of the circle over the side boards forces and gathers
the leather to the tree, at the instep with little labor and in a few minutes
and as the tree passes down between the side boards it completes the opera-
tion of cramping the leather.
